UNITED STATES PATENT OFFICE.

ROBERT R. KINTZ, OF MERIDEN, CONNECTICUT, ASSIGNOR TO INTERNATIONAL SILVER CO., OF MERIDEN, CONNECTICUT, A CORPORATION OF NEW JERSEY.

SALVER OR TRAY.

No. 811,299.

Specification of Letters Patent.

Patented Jan. 30, 1906.

Application filed May 15, 1905. Serial No. 260,546.

To all whom it may concern:

Be it known that I, ROBERT R. KINTZ, a citizen of the United States, residing at Meriden, in the county of New Haven and State 5 of Connecticut, have invented a new and useful Improvement in Salvers or Trays; and I do hereby declare the following, when taken in connection with the accompanying drawings and the numerals of reference marked 10 thereon, to be a full, clear, and exact description of the same, and which said drawings constitute part of this specification, and represent, in—

Figure 1, a top or plan view of a salver constructed in accordance with my invention; 15 Fig. 2, a sectional view thereof on the line *a b* of Fig. 1; Fig. 3, an under side view of the salver; Fig. 4, an under side view of the same with the bottom plate removed; Fig. 5, a 20 plan view of the block detached.

This invention relates to an improvement in salvers or trays, and particularly to such as consist of a metal border and a wooden center. In the usual construction of combined 25 wood and metal salvers the central portion is formed from wood and the edge of the border extends down onto its upper face.

The object of this invention is to form a portion of the bottom of the salver from 30 metal and provide it with a wooden central portion which does not necessarily follow the outline of the salver, whereby a great variety of designs may be employed; and the invention consists in the construction hereinafter 35 described, and particularly recited in the claim.

The salver may be of any approved form and design, the one herein shown having a bottom 2 and flange 3. A portion of the bottom 40 is removed, the cut-away portion leaving an outline of any desired shape. Preferably and as herein shown the under side of the bottom will be provided with a depending ring or collar 4. In place of the metal cut 45 out from the bottom of the salver I employ a block 5, which is preferably made up from several thicknesses of wood, so as to prevent warping, the upper thickness of wood preferably corresponding in thickness to the thickness of 50 the bottom 2. The upper thickness or a portion of the upper face 6 of the block corre-

sponds in outline to the outline of the cut-away portion of the bottom, so that the upper face of the block fits within the bottom and lies flush with the upper face thereof, 55 while the main portion of the block forms a shoulder 7, which bears against the under face of the bottom 2. This block may be secured in any desired manner. As herein shown, it is inclosed by a cup-shaped back 8, 60 the edges of which set within the ring 4, the depth of the back corresponding to the depth of the ring and to the thickness of the block, and this back may be held in place by screws 9, entering recesses or lugs 10, secured to the 65 under face of the bottom 2 of the salver. In forming the block the upper layer or face 6 may be formed from a veneer of any desired wood and so that with the same metal portions a variety of styles may be produced by 70 simply changing the wooden blocks. While the face of the blocks or upper layer of veneer will preferably be of hard wood, the main portion of the block may be of soft wood, although, if desired, a solid block may be 75 employed. If the block is formed with scallops, as shown, the lugs 10 for the reception of the screws will be placed between the scallops, so as to be as near the center of the salver as possible, and thereby more securely 80 hold the wooden block in place. As before stated, this construction permits the border of a salver and bottom thereof to be formed in the usual way by molding or stamping, and then the central portion may be cut out 85 in any desired design, either in the form of letters or geometrical figures, it being understood that the face of the block will correspond to the bottom of the cut-out portion of the salver and the upper face of the block and 90 the upper face of the bottom will be flush with each other.

Having fully described my invention, what I claim as new, and desire to secure by Letters Patent, is—

A salver comprising a bottom, a border and a depending collar, a portion of the bottom cut away, a block larger in dimensions than the cut-away portion and extending beneath the under face of the bottom, said 100 block formed with an upper face corresponding in thickness to the thickness of the bot-

tom and in outline to the cut-away portion through which it extends, and a cup-shaped metal back located within said collar and inclosing said block, and means for securing the back to the bottom whereby said block is held in position, substantially as described.

5 In testimony whereof I have signed this

specification in the presence of two subscribing witnesses.

ROBERT R. KINTZ.
